CLAIM

The ornamental design for horse stocks unit, substantially as shown and described.

DESCRIPTION

FIG. 1 is a top perspective view of a horse stocks unit showing my new design;

FIG. 2 is a side elevational view thereof;

FIG. 3 is an opposite side elevational view thereof;

FIG. 4 is an end elevational view thereof, the opposite end being substantially similar in appearance;

FIG. 5 is a top plan view thereof;

FIG. 6 is a top perspective view of an alternate embodiment thereof, the only difference residing in the jointure of the vertical upright elements with the horizontal top cross bar elements.

FIG. 1.

FIG. 2

FIG. 3

FIG. 4

FIG. 5

FIG. 6
